(57) **CLAIM**

The ornamental design for a sweat wicking headband assembly as shown.

DESCRIPTION

FIG. 1 is a left side perspective view of a sweat wicking headband assembly;

FIG. 2 is a front side view thereof;

FIG. 3 is a rear view thereof;

FIG. 4 is a right side view thereof; and,

FIG. 5 is a bottom view thereof.

The broken line outline of the partial human figure assists in illustrating how the sweat wicking headband assembly may appear when in a position of use, but forms no part of the claimed design.
